[57] CLAIM

The ornamental design for a video recorder bag, as shown and described.

DESCRIPTION

FIG. 1 is a perspective view of a video recorder bag, showing my new design, with a portion of the top turned back to reveal the zipper closure;

FIG. 2 is a right side elevational view;

FIG. 3 is a left side elevational view;

FIG. 4 is a top plan view;

FIG. 5 is a bottom plan view;

FIG. 6 is a front elevational view;

FIG. 7 is a rear elevational view with a portion of the top cut away to reveal the zipper closure; and

FIG. 8 is a perspective view thereof, with the top opened and a portion of the front broken away and omitted for convenience of illustration to show the inside of the bag.

Partial showing of surface shading indicating a fabric texture is understood to be continuous on those surfaces where shown.
